UNITED STATES PATENT OFFICE

GUSTAVE JACOBY, OF LOUISVILLE, KENTUCKY, ASSIGNOR TO THE ENRO SHIRT COMPANY, OF LOUISVILLE, KENTUCKY, A CORPORATION OF KENTUCKY

SOFT COLLAR

Application filed November 6, 1928. Serial No. 317,527.

This invention is an improvement in soft collars, and more particularly in means in connection with collars of this character for holding the outer fold at its free ends straight and smooth.

In the usual construction of collar of this character, the free ends of the outer fold tend to become crushed and wrinkled through contact with the shirt bosom, there being no stiffening at the said points to support said ends against the crushing and wrinkling which results from ordinary wear.

One of the primary objects of the present invention is the provision of a simple and inexpensive construction of collar, wherein means is provided in connection with the free ends of the outer fold, for receiving stiffening strips of suitable material, for holding the said free ends straight.

Another object is the provision of a form of holding means, which enables removal of the strips when the collar is to be laundered, and so constructed that the strips are held against accidental displacement when the collar is in use.

Another object is the provision of a holding means in the form of a pocket wholly on the inner surface of the fold, and indistinguishable at the outer surface, wherein the pocket is formed by a strip arranged transversely of the fold and secured to the inner ply thereof at the edges of the strip.

Another object is the provision of an opening in the pocket for the insertion and removal of the strip, in the form of a button-hole, reinforced to prevent damage to the same.

Another object is the provision of a reinforced opening in the form of a button-hole, accessible when the folds of the collar are moved into substantial alinement, but hidden when the collar is in position for use.

Another object is the provision of a holding pocket for a stiffening strip so constructed and arranged that it does not change the external appearance of the collar in any way.

With these and other objects in view the invention consists in the construction and novel combination of parts fully described hereinafter, illustrated in the accompanying

drawings, and pointed out in the claims appended hereto, it being understood that various changes in the form, proportion, size and minor details of construction within the scope of the claims, may be resorted to without departing from the spirit of the invention.

In the drawings forming a part hereof:—

Fig. 1 is a perspective view looking at the front of the improved collar.

Figs. 2 and 3 are sections on the lines 2—2 and 3—3 respectively, of Fig. 1.

Fig. 4 is a view of the inner face of the inner ply of the outer fold before its incorporation in the collar, and before the attachment of the pocket.

Fig. 5 is a similar view of the opposite face after the attachment of the pocket.

In the present embodiment of the invention the improved collar, which is of the soft or nonstarched type, is composed, as is usual, of an inner fold 1, and an outer fold 2, the said folds being of multiply construction, and attached together in the usual manner. The inner fold has the usual button tabs, one of which is shown at 3, and the outer fold at the ends thereof, is provided with means for preventing crushing or wrinkling of the said ends in the use of the collar.

The inner ply of the outer fold, indicated at 4 in Fig. 4, is provided with a button-hole 5 near the top edge thereof, and near the free end of the ply, that is, near that end which will be at the free end of the outer fold when the ply is incorporated in the collar. A strip 6 of suitable fabric material is arranged at the button-hole, and the button-hole is cut through the ply and through the reinforcing strip as shown. The button-hole is stitched in the usual manner by button-hole stitching indicated at 7, the stitching engaging both the ply and the reinforcing strip.

The reinforcing strip 6 is on the inner face of the ply, so that when the ply is incorporated in the collar, the reinforcing strip will be hidden, and only the button-hole will be visible. The reinforcing strip 6 is a little longer than the button-hole as shown, and of sufficient area to suitably reinforce the button-hole, and after the formation of the button-hole, as above specified, the pocket is attached.

The said pocket is secured to the inner face of the ply, and is composed of a strip 8 of suitable material, and width, which extends from the upper edge of the ply 4 to the lower edge. The edges of the strip 8 are substantially parallel with the edge of the end of the ply, and the strip is secured in place by lines of stitching 9 at the opposite side edges thereof, said lines passing through the ply. When 10 the ply is incorporated in the collar, the connection between the inner fold 1 and the outer fold 2, indicated at 10, closes the upper end of the pocket, and the lower end is closed by the connection of the plies of the outer fold, 15 said connection being indicated at 11.

As shown in Figs. 2 and 5, the button-hole 5 is spaced slightly below the bend indicated at 12, formed in the upper edge of the outer fold 2 when it is connected to the inner fold 1, and when the collar is properly folded as 20 shown in Figs. 1 and 2, this bend 12 forms what is in effect a closure for the button-hole or the opening of the pocket, to prevent displacement of the member 13, which is received 25 in the pocket. This member is a stiffening strip of suitable material, as for instance, celluloid, or the like, and it is easily inserted in the pocket when the folds 1 and 2 are in substantially the same place. When the parts are 30 shaped as shown in Figs. 1 and 2, the bend 12 prevents any displacement of the stiffening strip, but when the collar is to be laundered, for instance, the strip is easily removed.

It will be apparent from the description and the showing, that none of the stitching which connects the strip 6 or the strip 8 to the collar is visible at the outer face thereof. The strip 8 itself is on the inner face of the inner 35 ply 4, and only the two lines 9 of stitching are visible on the inner face of the collar. The stiffening strips hold the collar in its proper shape when in use, and after laundering, may be quickly inserted in the pockets. When in 40 the pockets there is no possibility of accidental displacement.

What is claimed as new is:—

1. A soft collar of the turned down type having a multiply outer fold, and having on 50 the inner ply on the face adjacent to the outer ply a transversely arranged strip connected to form a pocket by stitching to the inner ply, whereby the stitching is not visible on the outer face of the outer ply, and a stiffening 55 strip within the pocket, the inner ply having an opening at the end of the pocket near the junction of the fold to enable the insertion and removal of the stiffening strip.

2. A soft collar of the turned down type 60 having a multiply outer fold, and having on the inner ply on the face adjacent to the outer ply a transversely arranged strip connected to form a pocket by stitching to the inner ply, whereby the stitching is not visible 65 on the outer face of the outer ply, and a stiff-

ening strip within the pocket, the inner ply having an opening at the end of the pocket near the junction of the fold to enable the insertion and removal of the stiffening strip, said opening being reinforced on the face of 70 the inner ply adjacent to the strip.

3. A soft collar of the turned down type having a multiply outer fold, and having on the inner ply on the face adjacent to the outer 75 ply a transversely arranged strip connected to form a pocket by stitching to the inner ply, whereby the stitching is not visible on the outer face of the outer ply, and a stiffening strip within the pocket, the inner ply having an opening at the end of the pocket near 80 the junction of the fold to enable the insertion and removal of the stiffening strip, said opening being reinforced on the face of the inner 85 ply adjacent to the strip, and button-hole stitches encircling the opening connecting the reinforcing strip to the pocket strip and to the inner ply.

Signed at Louisville, in the county of Jefferson and State of Kentucky, this 29th day of October, A. D. 1928.

GUSTAVE JACOBY.
